CLAIM

The ornamental design for a camera, as shown and described.

DESCRIPTION

FIG. 1 is a top plan view of a camera;

FIG. 2 is a front elevation view thereof;

FIG. 3 is a bottom plan view thereof;

FIG. 4 is a rear elevation view thereof;

FIG. 5 is a left side elevation view thereof; and,

FIG. 6 is a right side elevation view thereof.

The broken lines depict portions of a camera in which the design is embodied that form no part of the claimed design.
